METHOD AND SYSTEM FOR MARKING
STAMPS

Morton Goldsholl, Northfield, Ill., assignor to Eureka-Carlisle Company, Scranton, Pa., a corporation of Delaware

Continuation of application Ser. No. 431,786, Feb. 9, 1965, which is a division of application Ser. No. 320,499, Oct. 31, 1963, now Patent No. 3,176,891, dated Apr. 6, 1965. This application Mar. 14, 1966, Ser. No. 533,964 1 Claim, (Cl. 283—62)

This application is a continuation of U.S. application Ser. No. 431,786 filed Feb. 9, 1965, now abandoned, which application was a division of U.S. application 320,499, filed Oct. 31, 1963, now U.S. Patent 3,176,891 granted Apr. 6, 1965.

This invention relates to stamps and more particularly to a method and system for marking stamps to facilitate the counting thereof for the purpose of dispensing same.

The use of stamps, particularly trading stamps, is becoming more prevalent in today's business world. Merchants have found that offering trading stamps with the purchase of goods or services can be a strong customer attraction. On the other hand these same merchants have found that the dispensing of such trading stamps can be an expense and a nuisance.

Trading stamps are usually dispensed in proportion to the customer's cash outlay for goods and/or services. If too few stamps are given to the customer, they may consider themselves cheated and never return. If too many stamps are given, the merchant's expense due to using such stamps rises. It is therefore important that the correct quantity of stamps be dispensed to each customer.

Merchants operating on a large scale volume, such as supermarkets or the like, can afford to use automatic dispensers which, in response to the push of a button or the rotation of a dial, dispense a measured quantity of stamps. However, many merchants, due to either the size of their business or the manner in which they serve their customers (such as service stations), find it impractical if not impossible to utilize an automatic dispenser and instead count off the stamps from either a roll or book of such stamps. For these merchants their hand counting of stamps is usually time consuming, very susceptible of error, and a nuisance.

To successively number each stamp or to number same in groups (1 to 10 and repeat) does not solve the hand counting problem since the stamps are usually printed with numerical values and are often overprinted with numbers to indicate lot, source, merchant or the like; all of which present to the person doing the counting a myriad of numbers which confuse the counting operation. Alphabetical lettering of successive stamps is just as confusing since the stamps are printed with letters to show whose they are and are also overprinted with letters to indicate lot, source, merchant and other control information.

In addition each stamp supplier has a design and color or pattern of colors to make their stamps distinctive and any system which upsets such design or color pattern (as by coloring entire areas of successive stamps different colors in repetitive groups) is also unacceptable.

It is therefore an object of this invention to provide a novel and improved method and system for marking stamps to facilitate the counting thereof.

It is another object to provide a novel and improved method and system for marking trading stamps to facilitate the counting thereof for the purpose of dispensing same.

2

It is a further object to provide a novel and improved set of markings to be placed in repetitive groups on successive ones of stamps, to facilitate counting of such stamps.

In carrying out this invention, according to a preferred embodiment, a set of nonalphanumeric symbols (neither letters of the alphabet or numbers) are arranged in predetermined order in repetitive manner and on successive stamps on a strip of stamps. By observing the number of stamps in each row of the strip of stamps (if there are more than one stamp in each row), by observing the number of symbols used, and by observing the number of times a symbol repeats one can easily and rapidly count the stamps.

The features and advantages of the invention will be seen from the above, from the following description of the preferred embodiment when considered in conjunction with the drawing, and from the claims.

The drawing shows a strip of stamps embodying the present invention.

For convenience the invention will be described with five different nonalphanumeric symbols disposed in a predetermined sequence and in a repetitive manner on the center column of a strip of stamps five stamps wide, in roll form, and being dispensed from a container such as the container shown in U.S. Patent 3,176,891; it being understood nevertheless that any convenient number of different symbols can be used, that such symbols can be disposed on one or more columns of stamps in the strip, that the strip can be one or more columns wide, that it can be in book form as well as roll form, and that it need not necessarily be associated with a dispensing device.

Referring now to the drawing, the numeral 20 generally designates a dispensing container of conventional construction, such as that shown in U.S. Patent 3,176,891 within which there is disposed a strip of stamps 22, in roll form, having five columns 24a, 24b, 24c, 24d, and 24e and a plurality of rows 26a, 26b, 26c, 26d, 26e, 26f, etc. of stamps 28.

A first symbol, 30, is disposed on stamp 28 in column 24c—row 26a; a second symbol, 32, is disposed on stamp 28 in column 24c—row 26b; a third symbol, 34, is disposed on stamp 28 in column 24c—row 26c; a fourth symbol, 36, is disposed on stamp 28 in column 24c—row 26d; and a fifth symbol, 38, is disposed on stamp 28 in column 24c—row 26e. The sequence of symbols 30, 32, 34, 36, and 38 is then repeated as long as required.

Assuming the user desires to count off a number of stamps they need only remember that the stamps are five wide and that the symbols repeat every five stamps. By observing the symbol on the first row of stamps and the number of times it repeats, if at all, the proper number of stamps is easily and rapidly dispensed.

While the symbols 30, 32, 34, 36, and 38 shown are of specific configuration it should be obvious that other suitable symbols (such as diamonds, hearts, pyramids, cylinders, etc.) can just as easily be employed.

Each stamp 28 of stamp strip 22 is printed, in conventional manner and according to the desires of the supplier, with a pattern 42 including numbers, letters, and one or more colors to make stamps 28 distinctive and easily identifiable to the users. In addition each stamp may be overprinted with letters 44 and/or numbers 46 to show lot, source, merchant, and other control information.

From the above description it will thus be seen that a novel and improved marking method and system has been provided, which, through the use of nonalphanumeric symbols placed in a predetermined order and in

a repetitive manner on successive ones of a strip of stamps, provides for an accurate, efficient and rapid counting of such stamps to facilitate dispensing thereof.

I claim:

An array of removably attached stamps each of which 5 is of a predetermined wording, denomination, and color pattern and each of which is adapted to be overprinted with numbers and letters; the stamps being arranged in columns and rows: comprising

- (a) a first identifying symbol; 10
- (b) a second identifying symbol;
- (c) additional identifying symbols;
- (d) said first identifying symbol, said second identifying symbol, and said additional identifying symbols, all being nonalphanumeric and being arranged in a 15 predetermined sequence and disposed on only a portion of the area on successive ones or a like prede-

termined number of stamps in one column of the array of stamps;

(e) said nonalphanumeric symbols being of a configuration and disposed on the stamps so as to be readily discernible thereagainst; and

(f) said predetermined sequence of symbols being further disposed in a repetitive manner on successive predetermined numbers of stamps in said one column to facilitate the counting of the stamps.
